UNITED STATES PATENT OFFICE.

WILLIAM E. SHORE, OF NEW YORK, N. Y.

PROCESS FOR THE CONSTRUCTIVE CONVERSION OF HEAVY TO LIGHT HYDROCARBONS.

Application filed December 26, 1923. Serial No. 682,602.

The principal objects of this invention are, to effect the production of the maximum percentage of hydrocarbons of a low boiling point from hydrocarbons of a high boiling point, and to accomplish such result in an economical manner.

Many different methods of conversion of hydrocarbons have been evolved such as distillation, cracking, catalyzing, or by spraying into gases, etc., many of which are more or less destructive.

The present process proposes a constructive conversion, the principal feature of which consists in atomizing or fogging the heavy hydrocarbons in association with hydrogen or hydrogen-bearing gases, and subjecting the mixture to mechanical and internal heat energy, associating the mixture with hydrogen or hydrogen-bearing gases to produce vapors, which vapors are maintained in suspension throughout the process.

The accompanying drawing is a diagrammatic view illustrating a suitable arrangement of apparatus for carrying this invention into effect.

It is the purpose of this invention to apply mechanical energy to break up or atomize the oil in the presence of hydrogen or hydrogen-bearing gases or vapors and to produce internal heat in this gas as the carrying medium for the hydrocarbon, the heat from the heat carrying medium being given up to the hydrocarbon; the entire mass being moved at high velocity through a system of pipes to a compressor, where final conversion takes place; preserving throughout a maximum heat energy, derived from mechanical energy for the purpose of maintaining or increasing the heat of the substances to be converted.

A prime mover for the system is illustrated in the form of a two cycle engine 1 which is shown directly connected with a reciprocating compressor 2. Power from the engine is transmitted in a suitable manner to a high speed rotary pump 3 which is of the type having a rotor eccentrically arranged in a cylinder and provided with vanes engaging the cylinder wall.

The oil to be treated is stored in a tank 4, and is pumped from said tank by a suitable form of circulating pump 5 through the pipe 5' to the jacket 6 surrounding the cylinder of the oil engine so that the radiated heat of the engine cylinder will be absorbed thereby.

The heated oil is conducted from the jacket

6 of the oil engine through the pipe 6 to the jacket 7 of the compressor 2, absorbing the radiated heat of the compressor. From the jacket 7 the oil is conveyed by the pipe 8 to the top of a suitable expansion reservoir 9, 60 which is preferably provided with a dome 10, so that any volatiles separating therefrom will be carried through a pipe 11, which contains a suitable pressure regulator 12, and is directed in to the feed pipe 13 to the compressor cylinder.

A pipe 14 leads from the bottom of the reservoir 9 and extends through the heater 15, which is heated by the exhaust from the engine 1.

The flow of oil through the pipe 14 is governed by a valve 16 leading to the intake conduit 17 to the rotary pump 3. This conduit 17 has connected to it several conduits which are adapted to convey the aforesaid 75 gases to the pump 3 to assist in expanding and atomizing the oil.

The use of hydrogen or hydrogen-bearing gases for mixing with the oil is advisable, as the hydrogen aids in subdividing or 80 atomizing the heavy liquid hydrocarbons, the process consisting not only in effecting a physical change by expanding and atomizing the oil in the suction chamber of the rotary pump, but thoroughly mixing therewith and building up the volume with a hydrogen bearing vapour, and it is because of this means that I term my method a constructive conversion.

A finely atomized condition is best effected in the presence of air or hydrogen or a hydrogen containing gas and the effect is two-fold. It not only aids in the atomizing, but under the pressure and at the temperature and velocity described, the minute mechanically subdivided particles are in a state of molecular 90 instability and due to this state of molecular instability, a chemical combination as well as a physical change takes place gradually and progressively without the aid of a catalyst between the oil and the hydrogen present in 100 the hydrogen-bearing gas, in which the oil particles are suspended.

The speed of the reaction is controlled by the temperature, velocity, pressure and other physical conditions present in each particular 105 stage of the process, and the most complete hydrogenation taking place at the last stage, or in the cylinder of the compressor, where it is subjected to the highest temperature conditions.

This process may be correctly termed a constructive conversion process, in contradistinction to destructive conversion, as illustrated in cracking processes, where the 5 ratio of hydrogen to carbon is increased by precipitating the excess carbon. It may be readily seen that in this process the hydrocarbon is actually brought into chemical combination with the enveloping hydrogen, 10 thereby increasing the yield of low boiling point fractions.

The gases are introduced in desirable proportions through the intake conduit 17 and through the operation of the atomizer pump 3, the mixture of gas and oil is first expanded 15 in the suction chamber of the pump and then it is compressed in the discharge end, the air or other gas acting as the expanding, compressing and carrying medium, transferring 20 the heat resulting from mechanical energy to all the molecules of the hydrocarbons.

This condition may be assisted by a suitable jacketing of the atomizing pump, which is here shown with a hollow jacket 18. This 25 jacket is preferably maintained at a uniform temperature by the circulation of a mercury vapour therethrough. The vapour may be produced by any suitable form of heater, but the heater is here shown in the form of a 30 jacket 19 surrounding a receptacle 20 which is connected with the bottom of the jacket 18 by the pipe 21. The exhaust gases pass from the heater 15 through the conduit 19' to the jacket 19.

35 A pipe 22 leads from the top of the receptacle 20 to the top of the pump jacket 18.

The atomized mixture, discharged from the atomizer pump 3, is conducted through a coil 23 arranged in the heater 15, and the 40 temperature of the mixture is raised therein by heat exchange with the exhaust gases of the engine. It is then conducted through a pipe 24 leading from the bottom end of the coil 23 to a coil 25 arranged within a drum 26.

45 The terminal end of the coil 25 leads to a similar coil within a drum 27, and the continuation of this coil leads through a pipe 28 to a coil in a third drum 29, from whence the vaporized mixture, which is being continuously raised in temperature in passage 50 through the coils, is conducted through the pipe 30 to the valve chest and cylinder of the compressor 2.

The temperature of the vaporized mixture in its passage from the atomizer pump 3 to the compressor is raised from approximately 250° F. to approximately 400° F., and when subjected to the operation of the compressor its temperature is again raised to 60 from 800° F. to 1200° F. This is an essential part of the process that cannot be over emphasized as the mechanical energy of the compressor is transformed into additional heat energy produced by the compression of 65 the mixture, and this heat energy is uniform

throughout the mixture and acts uniformly upon every particle, thus increasing the molecular instability of the hydrocarbon, and thereby increasing the capacity of the hydrocarbon molecules to combine with additional hydrogen, which combination is completed as the compression is carried out, thereby accomplishing the complete conversion to a lighter hydrocarbon. The highly vaporized mixture then passes through the conduit 70 to and through a series of drums 29, 27 and 26. The heat from this mixture in the said drums effects the raising of the temperature of the vapours, passing from the atomizing pump 3 through the conduits 25, 28 and 30 75 to the compressor.

A volatile vapour is conducted from the drum 26 to a series of expansion condensers 32, 33, and 34, wherein the different gravities of fluid are absorbed. Each condenser is 80 filled with hydrocarbon of the gravity of the fluid to be absorbed in that condenser. The hydrocarbon vapors under pressure are first conducted through the expansion valve 32' where they undergo free expansion with a 85 consequent drop in pressure and temperature. The hydrocarbon vapour is then conducted through a tube 33' into the hydrocarbon fluid in the condenser 32 and the vapour then passes upward through the condensing liquid hydrocarbon, with the result that all 90 of the vapour which is of the specific gravity of the condensing liquid is absorbed thereby, and the lighter hydrocarbons pass thence to the next expansion valve and condensing chamber 33 which contains liquid hydrocarbon of a lighter density with consequent 95 similar absorption of the next lighter oil, and so on progressively through the various controlling valves and condensers, filled with liquid hydrocarbons of increasingly lighter density, until all the condensable vapours are 100 condensed. The pressure within the various condensing chambers being governed in successive stages by the setting of the expansion valves 32' whereby the volume of flow into 105 each of the condensing chambers and consequently the pressure therein may be determined.

The condensing liquids in each condenser 110 will be maintained at the temperature below the condensation temperature of the vapours to be therein condensed by cooling with a water jacket. The hydrocarbons absorbed in the several condensers are carried to the receivers 35, 36 and 37 respectively.

A portion of the converted hydrocarbon vapour flowing from the drum 26 may be conducted through a pipe 38 back to the intake conduit 17 of the atomizer pump 3, to pass again through the cycle as described, when it is deemed desirable.

A pipe 39 is connected to the top of the final condenser and leads to the intake conduit 17 120 so that any uncondensed hydrogen-bearing 130

gases and vapours can be passed back through the system.

The high temperature oil vapour taken from the compressor and circulated through the expanding heating drums 29, 27 and 26 form a certain amount of condensate and this is conducted to a residual receiver 40 through the pipe connections 41 and 42. Provision is also made to carry off any condensation of oil particles in the atomizer pump 3 in the form of an oil trap 43 connected with the bottom of the atomizer pump 3 by a pipe 44, any condensed oil is carried back to the intake conduit 17 by a pipe 45.

15 The suction of the intake effects the evacuation of the oil from the trap 43.

In a process such as described it has been found that crude oils of either asphaltum or paraffin base may be combined in varying proportions with hydrogen containing gases by utilizing such gases as a medium for atomizing or disintegrating the heavy oils into a porous state, and these atomized heavy oils are maintained in suspension in the hydrogen-bearing gases by the internal heat of applied mechanical energy, such as has been described in addition to the heat absorbed from the exhaust from the engine. The results obtained are dependent upon the speed of movement 30 that is maintained throughout the process. Further, the rapidity of movement of the vapours is such that the percentage of heat transference to surrounding bodies is extremely low.

35 It is to be noted that throughout the process all material heat transference taking place is preserved within the system and is not lost to outside surrounding bodies, such as water cooled jackets or atmosphere, but the heat developed in one phase is conserved in the other; for instance, the heat of combustion in the engine is conserved in the passing of the oil through the surrounding jacket, likewise the heat of compression in the compressor is 40 transferred to the oil, which heated oil is later carried to the cylinder of said compressor.

In effect the process is carried out with a minimum loss of heat of the mechanical energy expended.

45 A process such as described is a distinct advance over the processes at present employed, such as distillation and cracking, as in both such systems the entire mass of the oil being treated is not subject to uniform conditions,

55 whereas with the present process the hydrogen-bearing gases are intimately associated and intermixed with the hydrocarbon particles from the commencement of the process in the atomizing pump 3; and at every stage of this process, every particle of the finely atomized mixture of hydrocarbon and hydrogen is subjected to similar temperature and pressure 60 conditions, which pressure and temperature are progressively increasing and produce increased molecular instability in the hydrocar-

bon molecules, until the combination of the hydrocarbon with its enveloping hydrogen is consummated in the compressor, with a minimum of residuals.

What I claim as my invention is:—

1. A process for converting heavy hydrocarbons to light hydrocarbons, comprising directing the oil through the jacket of a compressor, then introducing same in the presence of hydrogen bearing gases to a mechanically operating atomizer, then conducting the produced vapour to the compressor cylinder and raising its temperature under compression, then passing the highly heated vapour to expansion condensers.

2. A process for converting heavy hydrocarbons to light hydrocarbons, comprising directing the oil through the jacket of a compressor, then introducing same in the presence of hydrogen bearing gases to a mechanically operating atomizer, then conducting the produced vapour through heating coils, then compressing the heated vapour to a high temperature, then circulating the highly heated vapour through expansion drums enclosing said heating coils, and finally passing the vapour to a series of expansion condensers.

3. A process for converting heavy hydrocarbons to light hydrocarbons, comprising passing the oil through the jacket of an engine operating a compressor and an atomizer to absorb the excess heat, then passing it through the jacket of the compressor, then conducting it through a heater heated by the exhaust from the engine, then introducing same in the presence of hydrogen bearing gases to the atomizer, then passing the produced vapour through said exhaust heater, then conducting the superheated vapour to the compressor and compressing same to high temperature and finally condensing said vapour in stages to grade the lighter hydro-carbon product.

4. A process for converting heavy hydrocarbons to light hydrocarbons, comprising passing the oil through the jacket of an engine operating a compressor and an atomizer to absorb the excess heat, then passing it through the jacket of the compressor, then conducting it through a heater heated by the exhaust from the engine, then introducing same in the presence of hydrogen bearing gases to the atomizer, then passing the produced vapour through said exhaust heater, then conducting the expanded vapour through a series of heated coils, then conducting the superheated vapour to the compressor cylinder compressing same to a high temperature, then conducting said compressed vapour around said heated coils, then expanding the compressed vapour and condensing same in stages.

5. A process for converting heavy hydrocarbons to light hydrocarbons comprising forcing a continuous flow of oil through an engine cylinder jacket to and through a com-

- pressor jacket to a mechanical atomizer, mixing therewith hydrogen bearing gases and delivering an atomized vapour at high velocity through a series of heated coils to a compressor operated by said engine, then expanding the compressed vapour at high velocity through a series of drums and finally expanding and condensing the vapour in a series of condensers.
6. A process for converting heavy hydrocarbons to lighter hydrocarbons, comprising first subdividing the hydrocarbons in the presence of supporting hydrogen-bearing gases, passing the said mixture at high velocity through an orifice to a mechanically operated periodically enlarged heated chamber, then compressing and discharging the mixture against a substantially continuous pressure flow, then conducting said mixture through varying heat transference zones progressively increasing the temperature of the mixture under a continued pressure flow, then further compressing said mixture to cause a further increase in temperature uniformly throughout the mixture thereby progressively increasing the molecular instability of the hydrocarbons receiving the hydrogen until conversion is completed, then conducting the converted mixture to expansion conditions dropping in successive stages the temperature and pressure, then condensing the hydrocarbon vapours into the various gravities of hydrocarbons by passing the condensable hydrocarbons through hydrocarbon liquids in stages of varying gravity.
7. A process for converting heavy hydrocarbons to lighter hydrocarbons, comprising first subdividing the heavy hydrocarbon in association with and in suspension in hydrogen or hydrogen-bearing gases, then moving the mixture at a high velocity through an orifice to a sealed periodically enlarged heating chamber expanding the suspension medium enveloping the heavy hydrocarbon particles, then compressing same producing internal heat uniformly among the suspended molecules of hydrocarbon and the hydrogen-bearing gases, then discharging under a pressure flow producing molecular instability in the hydrocarbon particles and utilizing the internal heat energy to start the combining of the hydrogen with the hydrocarbon, then passing the mixture through a heat exchange vaporizing the lighter hydrocarbons and uniting hydrocarbon vapours with hydrogen to produce a lighter hydrocarbon vapour, then further compressing the vapour producing pressure and temperature by mechanical energy, the hydrogen-bearing gases and the formed hydrocarbon vapours acting as the further carrying medium for the hydrocarbon, then giving up this internal heat from this carrying medium to the hydrocarbons circulated around the compression chamber producing in them a chemical reaction
- then passing the converted hydrocarbon mass through progressive stages of condensation.
8. A process for converting heavy hydrocarbons to light hydrocarbons comprising in forcing a continuous flow of oil through an engine cylinder jacket to and through a compressor jacket to a mechanical atomizer, mixing therewith hydrogen bearing gases and delivering an atomized vapour at high velocity through a series of heater coils to a compressor operated by said engine, then expanding the compressed vapour at high velocity through a series of drums, said drums enclosing the heater coils leading to the compressor, and finally conducting the vapour through a series of condensers.
9. An apparatus for converting heavy hydrocarbons to light hydrocarbons comprising, an internal combustion engine having its cylinder jacket connected with an oil supply, a pump for circulating the oil through said jacket, a compressor operated by said engine and having its cylinder jacket connected with the engine cylinder jacket, a heat jacketed mechanical atomizer having its intake connected with the compressor jacket, means for introducing gases to said atomizer with the oil, means for conducting the vapour from the atomizer to the compressor, means for expanding said compressed vapour, and means for condensing the expanded vapour in stages.
10. An apparatus for converting heavy hydrocarbons to light hydrocarbons comprising, an internal combustion engine having its cylinder jacket connected with an oil supply, a pump for circulating the oil through said jacket, a compressor operated by said engine and having its cylinder jacket connected with the engine cylinder jacket, a heat jacketed mechanical atomizer having its intake connected with the compressor jacket, means for introducing gases to said atomizer with the oil, an exhaust heater connected with the engine exhaust, means for conducting the vapour from the atomizer through said heater, heater coils conducting said vapour to the compressor, drums enclosing said heater coils and connected in series with said compressor, and expansion condensers arranged in series and connected with said drums.
11. An apparatus for converting heavy hydrocarbons to light hydrocarbons comprising, an internal combustion engine having its cylinder jacket connected with an oil supply, a pump for circulating the oil through said jacket, a compressor operated by said engine and having its cylinder jacket connected with the engine cylinder jacket, a heat jacketed mechanical atomizer having its intake connected with the compressor jacket, means for introducing gases to said atomizer with the oil, an exhaust heater connected with the engine exhaust, means for conducting the vapour from the atomizer through said heater,

heater coils conducting said vapour to the compressor, drums enclosing said heater coils and connected in series with said compressor, expansion condensers arranged in series and connected with said drums, and means for conducting heated vapours from said drums to the intake of the atomizer.

12. An apparatus for converting heavy hydrocarbons to light hydrocarbons comprising, an internal combustion engine having its cylinder jacket connected with an oil supply, a pump for circulating the oil through said jacket, a compressor operated by said engine and having its cylinder jacket connected with the engine cylinder jacket, a heat

jacketed mechanical atomizer having its intake connected with the compressor jacket, means for introducing gases to said atomizer with the oil, an exhaust heater connected with the engine exhaust, means for conducting the 20 vapour from the atomizer through said heater, heater coils conducting said vapour to the compressor, drums enclosing said heater coils and connected in series with said compressor, expansion condensers arranged in series and 25 connected with said drums, and means for conducting uncondensed gases from said condensers back to the cycle.

WILLIAM E. SHORE.
